(57) **CLAIM**

An ornamental design for a front turn signal for a vehicle, as shown and described herein.

DESCRIPTION

FIG. 1 illustrates a perspective view of a new and ornamental front turn signal for a vehicle;

FIG. 2 illustrates a front view thereof;

FIG. 3 illustrates a back view thereof;

FIG. 4 illustrates a left-side view thereof;

FIG. 5 illustrates a right-side view thereof;

FIG. 6 illustrates a top view thereof; and,

FIG. 7 illustrates a bottom view thereof.

The broken lines in the figures depict portions of the front turn signal for a vehicle that form no part of the claimed design.
